(57) CLAIM

The ornamental design for a cowboy cap, as shown and described.

DESCRIPTION

FIG. 1 is a perspective view of a cowboy cap.

FIG. 2 is a front view thereof;

FIG. 3 is a rear view thereof;

FIG. 4 is a right-side view thereof;

FIG. 5 is a left-side view thereof;

FIG. 6 is a top view thereof;

FIG. 7 is bottom view thereof; and,

FIG. 8 is another perspective view of the cowboy cap shown in an alternate environment.

The broken line outline of the headwear visors depict environment associated with the cowboy cap, but form no part of the claimed design. The broken lines along the crown interior of the cowboy cap in FIG. 7 depict portions of the article that form no part of the claimed design.
